CRANE HOIST CONTROL

Glenn A. Caldwell, Edgewood, Pa., assignor to Westinghouse Electric & Manufacturing Company, East Pittsburgh, Pa., a corporation of Pennsylvania

Application May 5, 1939, Serial No. 271,879

2 Claims. (Cl. 172—179)

My invention relates to a control system for an electric motor and is particularly applicable to a motor utilized for operating load hoisting or elevating devices or load lowering devices, such as cranes and the like.

An object of my invention is to provide a system of control that embodies a minimum number of units and which is simple and reliable in operation, and inexpensive to manufacture.

10 Another object of my invention is to provide a control system which has substantially ideal or most desirable speed torque curves for a hoist motor when operating in the lowering direction.

15 A more specific object of my invention is to provide a split series field winding for the hoisting motor comprising, a main portion and an auxiliary portion, and which is so arranged that the auxiliary portion will provide a cumulative field when the motor is operating in the lowering 20 direction with an overhauling load, that is, when the motor is providing regenerative current and, in effect, is acting as a generator.

Other objects and advantages will become more apparent from a study of the following specification when considered in conjunction with the accompanying drawings, in which:

Figure 1 is a diagrammatic showing of a complete system of control embodying my invention;

Fig. 2 shows the motor circuit for the fifth controller position of hoisting;

Fig. 3 shows the motor circuit for the fifth controller position during the lowering operation;

Fig. 4 shows a series of samples of speed torque curves for control systems conventional in the art for all the controller positions of the motor when the motor is operating in the lowering direction; and

Fig. 5 is a sequence chart showing the sequence of operation in the various switches in the motor 40 circuits both for the hoisting and the lowering operation.

In a crane hoist control it is desirable to obtain as high a speed as possible for the crane hook when lowering empty, and at the same time 45 not obtain an excessive speed when lowering with a heavy load. Referring to the speed torque curves in Fig. 4, which are illustrative of control systems which are conventional in the art, it will be noted that when the load is overhauling, the 50 hoist motor is used to develop a braking torque, the figure showing that with 63% field current, the increase in speed with load is appreciable but not dangerous. The figure also shows the performance of the motor in one instance with 37% 55 field current and another with 24% field current,

where with less than full load on the hook, the hoist motor would run away.

In accordance with my invention, the above-mentioned runaway condition will be eliminated and the speed torque curves for low values of field current will be substantially flattened, very much like those illustrating 44% and 63% field current.

Referring more particularly to Fig. 1 of the drawings, M designates the hoisting motor to be 10 controlled and B and C refer, respectively, to the brake winding and the commutating field winding for the motor. F and F' refer to a split 15 series field winding in which F is the main portion and F' is an auxiliary portion. A control system is illustrated for the motor and is shown in the deenergized position. A controller 100 may be of any desirable type, such as the drum type having a plurality of contact segments for varying the circuit connections for different positions in 20 the hoisting or lowering direction. Five positions are shown for the hoisting direction and five positions are also shown for the lowering direction, for giving various values of speed and torque to the motor in these directions. Contact members 25 1 to 11, inclusive, are operable by relays 1A to 11A, inclusive, respectively, to secure various circuit combinations in the hoisting and lowering directions. Contact members 12 to 15 inclusive, are operable by time limit relays 12A to 15A 30 inclusive, respectively. The time limit relays 12A to 15A inclusive, have main coils 12M to 15M, inclusive, and neutralizing coils 12N to 15N inclusive, respectively. Each of these relays is biased in one direction by a spring as shown. A 35 relay rheostat 16 is provided for adjusting the time constant of the relays. It will be noted that the springs associated with each of the relays is also adjustable, thereby providing additional adjustability of the time constant of the relays. The operation of these time limit relays forms no part of my invention, but to preferably describe their operation it may be generally stated that relay 12A holds one of its associated contacts closed in the lowering operation long enough to insure release of the brake, and prevents closing of contact members 8 in the lowering direction until contact members 12 are open. Time limit relay 13A picks on the fourth point lowering and holds contact members 14 closed to provide a 40 regular braking circuit and contact members 13 open to prevent application of the emergency braking circuit for a fraction of a second if the master switch is returned suddenly to the "off" position.

By referring to Fig. 5, which is a sequence chart showing the sequence of operation of the various switches in the motor circuits for both hoisting and lowering operations, the particular circuit for any of the five positions of hoisting or lowering can be identified. Inasmuch as my invention is not concerned with the successive steps or positions in the operation of the motor either in the hoisting or in the lowering direction, 10 it is deemed that a detailed explanation of each successive position in hoisting or lowering is unnecessary. Furthermore, the control system illustrated in the figures together with the sequence chart in Fig. 5 will readily disclose to those familiar with the art what is included in the various circuits in each successive position for both hoisting and lowering. It is felt that a detailed explanation of each step would be not only superfluous, but would tend to confuse 15 the reader as to the essence of the invention. However, to briefly summarize the successive operations in both hoisting and lowering operation, it may be stated that in all five positions of hoisting, all of the field coils (see 20 F and F') together with the braking field coil, are connected in series with the incoming power line, hence the motor operates as a series motor. Fig. 2, which shows the fifth position of hoisting, is illustrative of this series connection. On the other hand, on all five positions of lowering, the 25 main field coil F together with the commutating field coil C and the braking field coil B, are connected in parallel with motor M, whereas the auxiliary field coil F' still remains in series in motor M; hence motor M operates as a shunt motor. Fig. 3 is an illustrative showing of the fifth position of lowering. In the hoisting operation, the full value of starting resistance is connected 30 in series with the various field coils, brake coil and motor and, in general, by going through the five successive steps, the starting resistance is gradually shunted out by successive increments until finally, as shown in Fig. 2, representing the fifth hoisting position, the starting resistance is 35 completely shunted out and the motor with its various field coils and brake coil is connected directly across the line. On the other hand, in the lower operation in going from the first to the fifth position, resistance is gradually inserted 40 in series with the shunt field in successively greater amounts until finally, as will be noted from Fig. 3 illustrating the fifth lowering position, the full value of resistance is inserted in series with the shunt field. As it will be obvious 45 to those skilled in the electrical art, as the resistance is gradually decreased in going from the first to the fifth position in the hoisting operation of a constant load when the motor M is connected as a series motor, the speed and torque 50 thereof will gradually increase. On the other hand, in the lowering operation, as the resistance in series with the shunt field is gradually increased so as to gradually weaken the shunt field, the speed of the motor and the torque thereof 55 gradually increases.

My invention is specifically directed to the split field series winding F and F' in which the auxiliary portion F' is preferably 10% or less of the field strength of the main portion F. As will be noted from Figs. 2 and 3, the auxiliary portion F' is always connected in series with the motor M in both hoisting and lowering operations. However, the main portion F is connected in series with motor M in all five positions of hoisting (as 60 illustrated in Fig. 2) but is connected in parallel

with motor M in all five positions of lowering (illustrated in Fig. 3). When motor M acts as a motor, for example, in all five hoisting positions and under certain conditions of lowering, field F' will buck the main field F. This, however, 5 will not be objectionable as long as the auxiliary field F' is not over 10% of the field strength of the main field F. When lowering a very heavy load, that is, an overhauling load, a regenerative current is obtained and motor M will, in effect, 10 act as a generator and will generate current in a direction opposite the motor current. Hence the auxiliary field F' and the main field F will be cumulative and will decrease the speed and tend to keep speed torque substantially flat. In this 15 manner, when a heavy overhauling load is being lowered, a dangerously high speed will be avoided. Furthermore, inasmuch as the split field coils are permanently in the circuit, a gradual braking action will be secured which is a substantial improvement over the well-known control systems 20 employing relays and the like wherein abrupt changes are secured for the purpose of checking excessively high speed, but which abrupt changes are detrimental to safe operation of a crane hoist. Obviously, any sudden change in the speed 25 of the crane either in the raising or lowering position might cause a shaking off of the load, which would be highly dangerous, and at the same time, the control of the crane would be very 30 confusing and difficult.

Many protective features usually embodied in control systems of this kind such as overload and undervoltage protection, have been omitted 35 for the sake of simplicity, but it is understood, of course, that these features may be incorporated in the above described control system.

I am, of course, aware that others, particularly after having had the benefit of the teachings of my invention, may devise other devices embodying my invention, and I, therefore, do not wish to be limited to the specific showings made in the drawings and the descriptive disclosure hereinbefore made, but wish to be limited only by the scope of the appended claims and such prior art 45 that may be pertinent.

I claim as my invention:

1. A control system for a hoist motor for operating a crane or the like, comprising, in combination, a hoist motor having an armature winding and having a split field winding, said split field winding including a main portion and an auxiliary portion, circuit means for connecting said main portion in series with the said armature winding of said motor during hoisting operation and in parallel with said armature winding during lowering operation, control means for controlling said circuit means, said auxiliary portion being permanently connected in series with said armature winding, said portions being wound 50 so that their field strengths are cumulative during lowering operation when said motor is acting as a generator due to regenerative current developed as the result of an overhauling load, thereby slowing down said motor and which field strengths 55 are in bucking relationship when said motor is acting as a motor, thereby speeding up said motor, and a commutating winding also permanently connected in series with said armature winding and said main portion of said split field winding. 60

2. A control system for a hoist motor for a crane or the like comprising, in combination, a hoist motor having an armature winding and having a split field winding including a main portion and an auxiliary portion, circuit means for con- 75

necting said main portion in series with the armature winding of said motor during hoisting operation and in parallel circuit relation with said armature winding during lowering operation, control means for controlling said circuit means, said auxiliary portion being permanently connected in series with said armature winding, said portions of said split field winding being wound so that their field strengths are cumulative during lowering operation when said motor is acting as a generator due to regenerative current developed as a result of an overhauling load,

thereby decreasing the speed of said motor and which field strengths are in bucking relationship when said motor is acting as a motor, thereby increasing the speed of said motor, said auxiliary portion being operable to develop a field strength which is normally less than 10% of the field strength of said main portion and a commutating winding permanently connected in series with said armature winding and main portion of said split field winding.

GLENN A. CALDWELL.
